National Steel Corporation, a corporation of Delaware

Filed Mar. 7, 1967, Ser. No. 6,109

Term of patent 14 years

(Cl. D58—26)

FIG. 1

FIG. 2

FIG. 3

FIG. 1 is a top plan view of an end closure for a container embodying my new design;

FIG. 2 is a sectional view taken along lines 2—2 of FIG. 1 in an embodiment wherein the reinforcing rib is depressed in the panel of the end closure; and

FIG. 3 is a sectional view of an end closure for a container showing another form of my new design wherein the reinforcing rib is provided in raised relationship to the panel of the end closure.

I claim:

The ornamental design for an end closure for a container, substantially as shown and described.
